UNITED STATES PATENT OFFICE.

JAMES W. NEWMAN, OF PLAINVIEW, OREGON.

LAND-ROLLER.

SPECIFICATION forming part of Letters Patent No. 634,737, dated October 10, 1899.

Application filed August 8, 1899. Serial No. 726,581. (No model.)

To all whom it may concern:

Be it known that I, JAMES W. NEWMAN, a citizen of the United States, residing at Plainview, in the county of Linn and State of Oregon, have invented certain new and useful Improvements in Land-Rollers; and I do declare the following to be a full, clear, and exact description of the invention, such as will enable others skilled in the art to which it appertains to make and use the same.

My invention relates to improvements in land-rollers; and the object is to provide a simple, inexpensive, and durable form of implement of this class that will adjust itself to the inequalities of the ground and permit the turning of corners and the return angles at the ends of the rows with facility.

To this end the convention consists in certain features of construction and combination of parts, which will be hereinafter more fully described and claimed.

In the accompanying drawings the same reference characters indicate the same parts of the invention.

Figure 1 is a perspective view of my improved land-roller. Fig. 2 is a top plan view of the same. Fig. 3 is a similar view showing the position of the roller in turning a curve or corner. Fig. 4 is a side elevation of the roller.

1 denotes the tongue fixed to the transverse beam 2, which in turn is connected to the parallel beam 3 by the end bars 4 4, in which the forward roller 5 is mounted.

6 denotes the seat, and 7 7 the diagonal braces, which extend from the tongue to the outer ends of the beam 2, the rear ends of said braces being formed with eyes 7' to receive the forward ends of the diverging draft- rods 8 8, which extend through the ends of the beam 2 and eyes 7' and are provided with the nuts 9 9 to clamp the eyes 7' against said beam. The rear ends of the draft-rods 8 8 are fixed to the beam 3 by the clips 9 9, and

their immediate ends terminate in the hooks 45 10 10, which engage the eyes 11 11 on the yoke-straps 12 12, in which the rear rollers 13 13 are mounted. These latter rollers carry boxes 14 14, which may be loaded with stones or scrap metal to give additional weight. 50

It will be noted that the rear rollers are pivoted to the draft-bars and turn independently and without interference with each other or with the front roller, as shown in Fig. 3, thus enabling the operator to turn very 55 sharp corners and manipulate the implement in confined spaces.

The accompanying drawings show my invention in the best form now known to me; but many changes in the details might be 60 made within the skill of a good mechanic without departing from the spirit of my invention as set forth in the claims at the end of this specification.

Having thus fully described my invention, 65 what I claim, and desire to secure by Letters Patent of the United States, is—

1. In a land-roller, the combination with the main-roller frame, of the draft-rods fixed to said frame and terminating in the hook-shaped ends and the rear rollers pivoted to said draft-rods, substantially as and for the purpose set forth. 70

2. A land-roller comprising the tongue 1 and beams 2 and 3, the diagonal braces 7 7 formed with the eyes 7', the draft-rods 8 8 formed with the hooks 10 10, the yoke-straps 12 12 formed with the eyes 11 11 and the rollers 13 mounted in said yoke-straps, substantially as and for the purpose set forth. 75 80

In testimony whereof I have hereunto set my hand in presence of two subscribing witnesses.

JAMES W. NEWMAN.

Witnesses:

A. B. WILMOT,
C. J. SHEDD.
